CLAIM

The ornamental design for a retail product display stand, as shown.

DESCRIPTION

FIG. 1 is a perspective view of the retail product display stand of the present invention;

FIG. 2 is a top view of FIG. 1;

FIG. 3 is a side view of FIG. 1, the opposite side being a mirror image;

FIG. 4 is a front view of FIG. 1; and,

FIG. 5 is a front view similar to FIG. 4, with environmental features shown in broken lines for purposes of illustration only and forming no part of the claimed design.
